(57) CLAIM

The ornamental design for a leg for furniture, as shown and described.

DESCRIPTION

FIG. 1 is a front, top, and right perspective view of a leg for furniture showing our new design;

FIG. 2 is a rear, top, and left perspective view thereof;

FIG. 3 is a top plan view thereof;

FIG. 4 is a front view thereof; and,

FIG. 5 is a right side view thereof, the left side view being a mirror image thereof.

The broken lines illustrate portions of the leg for furniture that form no part of the claimed design.
